UNITED STATES PATENT OFFICE

ERICH KRUHME, OF BERLIN-TREPTOW, AUGUST JIPP AND EHRHARD ROSSBERG, OF BERLIN-SIEMENSSTADT, GERMANY, ASSIGNEES TO SIEMENS & HALSKE AKTIEN-GESELLSCHAFT, OF SIEMENSSTADT NEAR BERLIN, GERMANY, A CORPORATION OF GERMANY

SYSTEM OF COMMUNICATION BY MEANS OF CURRENT IMPULSES

Application filed February 19, 1931, Serial No. 516,908, and in Germany February 7, 1930.

Our invention relates to electric telegraph systems, and particularly to such as employ printing telegraphs.

The main purpose of this invention is to provide, at one or more points of the transmission system, distortion-correcting devices (regenerative repeaters) by which the signals received are transmitted or carried on in a form free from distortion. It is also an object of the invention to provide means for the transmission of currents other than telegraphic currents, without any detrimental action on said repeaters, and without said repeaters impairing the transmission of such other currents.

In the transmission of current impulses the shape of the curve, in particular the length of the individual current impulses, is changed (distorted) along the path from the transmitter to the receiver by various causes, primarily the electric properties of the means of transmission. If the distortion becomes so strong that a reliable reception of the current impulses at the receiving end is no longer possible, it is necessary to employ a suitable correcting or anti-distortion device for eliminating, either completely or substantially so, the distortion of the current impulses which has occurred.

For correcting the telegraph signals, there have been employed hitherto relay transmitters or repeaters which in their operation differ from each other as to the timing of the opening and closing of their contacts, and which are interposed at a suitable point in the path of transmission. If it is desired to use only a relatively small number of such apparatus, the degree of correction obtainable is limited and in many cases inadequate for practical use. Moreover, there arises the danger that a certain error will occur at each transmission and that such errors will be added to one another when the transmission is made through several successive repeaters.

For this reason, certain types of telegraph systems make use of rotary repeaters which in their mode of operation must be adapted to the particular type of the telegraph system employed. In high-speed telegraph plants which operate with telegraph signals com-

posed of groups of current impulses, and require accurate synchronism of the transmitting and receiving distributors for the correct transmission of the signals, rotary repeaters have been employed, which consist substantially of a receiving distributor coupled rigidly with a transmitting distributor of the type employed in high-speed telegraphy. The individual current impulses reaching the receiving distributor are passed through the individual distributor segments to impulse storing or holding devices which in their turn connect the voltages corresponding with the individual current impulses to the segments of the transmitting distributor. For the correct operation of this repeating apparatus it is necessary to secure accurate synchronism of the distributors with the other transmitting and receiving distributors of the high-speed telegraph line employed.

In high-speed telegraphy, the groups of current impulses follow one another in continuous sequence at constant intervals. In telegraph systems operating on the start-stop principle and in similar systems, the groups of current impulses succeed one another at intervals of varying length, and in connection with such systems there are employed distortion-correcting repeaters which, instead of rotating continuously, are started either in response to the first current impulse or by a special starting impulse at the beginning of each group of current impulses. In this case the distributors of the distortion-correcting repeater require only a relatively small degree of accuracy as to their synchronism with the distributors of the telegraph apparatus, in accordance with the relatively low degree of synchronism accuracy customary in such apparatus. In this case also, there is employed in conjunction with such repeaters, a receiving distributor which receives the arriving current impulses of each group and transmits them individually to the storing devices which effect the distortionless further transmission; there is also used, if desired, a transmitting distributor which passes the stored impulses on to the next section of the line.

The application of the described transmission apparatus leads to certain troubles in the case of plants in which in addition to the normal telegraph signals special current impulses are to be transmitted, which in their properties are different from the telegraph signals proper. This is the case in telerecording plants with selector operation, as in these plants in addition to the signals employed for the telerecording traffic the selector impulses serving for the setting of the connecting apparatus as well as, in some cases, further impulses, such as signal impulses, have to be transmitted. The difficulty arising in such cases consists in the fact that the correcting repeating apparatus which must be connected at a suitable point in the connecting line, does not permit of a correct transmission of the impulses which differ from the telegraph signals.

These difficulties may according to our invention be eliminated by providing switch-gear for by-passing or disconnecting the correcting current impulse repeaters, which permit the transmission of the currents differing from the telegraph impulses. The disconnection of the current impulse repeaters will be advisable particularly then when the telegraph impulses as well as the impulses different from them are direct current impulses, while in the event of partial or exclusive use of alternating current for the impulses a by-passing of the current impulse repeaters by the use of filters well known in the art may be preferable.

The mode of operating the current impulse repeaters may, in particular, be such that they are able to transmit only during the telegraph traffic, by being, for example, connected in circuit at the commencement of the traffic and disconnected when the traffic is finished. The process of connecting or disconnecting the apparatus provided for by-passing the current impulse repeaters is to be considered equivalent with the process of connecting or disconnecting the current impulse repeater itself. For plants in which exchange equipment is employed, more particularly in plants with selector or dial operation, a simple solution results from the fact that the effect of the current impulse repeater or the by-pass equipment depends upon switching means which become operative when the connection is made or broken. In telerecording plants with dial operation the control of the current impulse repeaters or their by-pass devices may take place by giving, after the desired subscriber has been reached, a disengaged signal which differs from the disengaged signals of the individual selector steps. This special disengaged signal may then control in the repeater apparatus, a relay which eliminates the by-pass of the correcting repeater existing in the state of rest. It is then, of course, easily possible

to use special repeater apparatus for repeating the impulses which are different from the telegraph impulses proper, and which, if desired, may work without correction.

Further details of our invention will be understood from the following specification and the drawings affixed to it. The embodiment of our invention illustrated by way of example is based upon the assumption that telerecording plant working on the start-stop principle are employed in which the signal composed of five current impulses is initiated by a start impulse and, as a rule, finished by a stop impulse.

In the drawings:

Fig. 1 is a diagrammatic view showing the arrangement and wiring for a correcting repeating system such as may be used in connection with our invention, while the remaining figures illustrate the connection of such a repeater apparatus in the system of an automatic exchange for telerecording subscriber stations,

Fig. 2 is a diagram of a complete telerecording system, while

Figs. 3 to 6 illustrate details of the wiring diagram, and

Fig. 7 the wiring diagram of the plant into which they are to be combined.

Referring to Fig. 1 of the drawings, the repeater system consists substantially of the receiving relay ER connected in the incoming line L_1 , which relay in alternating current operation is designed as a polarized relay, the receiving distributor V_1 , the impulse storing relays R_1 to R_5 and the transmitting distributor V_2 connected in the outgoing line L_2 . Each of the two distributors possesses a segment ring S_1 or S_2 respectively made with six sections 10 to 15 or 20 to 25 respectively and a solid ring which is successively connected to the individual sections of the segment ring when the wiper B_1 or B_2 respectively rotates. The wipers are held in the inoperative position by locking levers H_1 and H_2 respectively. The release takes place when the release magnets AM_1 or AM_2 are energized.

With the wiper B_1 is rigidly connected a cam C which controls a switch contact AK. This contact is connected in the circuit of the release magnet AM_2 of the transmitter distributor V_2 and effects its release after the receiver distributor V_1 has started. The relative timing of the two rotations depends upon the angular position of the cam C. Simultaneously with the release magnet AM_2 there is energized a release and holding relay AHR which causes the retransmission of the start impulse into the outgoing line L_2 .

The system illustrated functions in the following manner, upon the reception, over the line L_1 , of a telegraph signal consisting of a release current impulse and the five signal current impulses as well as, in some cases,

a holding current impulse: The release current impulse by energizing the receiving relay ER first changes the connection of the armature of the relay from the positive pole 5 on to the negative pole of the local battery OB. The following circuit for the release magnet of the receiving distributor is then completed: negative pole of the battery OB, armature of the receiving relay ER, solid 10 contact ring of the receiving distributor V_1 , wiper B_1 , zero segment 10 of the segment ring S_1 , release magnet AM_1 , positive pole of the battery OB. The locking lever H_1 is released and sets the wiper free to perform one revolution. The wiper then sweeps 15 across the individual segments 11 to 15 of the segment ring S_1 which are connected to the storing relays R_1 to R_5 .

As the speed of rotation of the wipers is adapted to the telegraphing speed, the storing relays R_1 to R_5 are successively energized 20 when the wiper sweeps across the segments 11 to 15, in correspondence with the individual current impulses. If, for example, the first signal current impulse is opposed to the release current impulse, the following circuit is completed at the moment when the wiper B_1 makes contact with the segment 25 11: ground, half of the battery OB (positive pole), armature of the relay ER (meanwhile turned back into the position illustrated), wiper B_1 , contact segment 11, storing relay R_1 , ground. The armature of the storing relay R_1 , for instance, is thereby brought 30 into the position illustrated. The adjustment of the remaining storing relays R_2 to R_5 is effected in a similar manner.

Partly positive and partly negative potential is now applied to the signal current segments of the segment ring S_2 of the transmitting distributor, according to the composition of the telegraph signal and the corresponding adjustment of the storing relays. If thus the distributor brush B_2 is released, 40 the outgoing line L_2 is through the solid contact ring of V_2 successively connected with + and - respectively through the individual segment sections 21 to 25. The release takes place as soon as the cam C connected with the wiper B_1 of the receiving distributor closes the release contact AK. The release magnet AM_2 is thus energized which releases the wiper B_2 by operating the locking lever H_2 , and simultaneously the holding relay AHR 45 is made to respond, which turns its armature temporarily from the position of rest into the working position. In this working position the negative pole of the battery is connected to the outgoing line L_2 thereby effecting the 50 transmission of the release impulse across the circuit: ground, half of the battery OB (negative pole), armature of the relay AHR, rest segment 20, wiper B_2 , line L_2 . When the wiper B_2 has left the zero segment, the release contact AK is again opened, so that the

locking lever H_2 as well as the armature of the relay AHR return into the inoperative position. By the armature of AHR the positive pole of OB is connected to the zero magnet 20, so that after the revolution is finished 70 the wiper B_2 on running on to the zero segment sends a clearing impulse into the line L_2 .

The repeater equipment illustrated in Fig. 1 must be understood as an example only, and instead of it we may use any other customary or approved arrangement.

By using known connections the repeater system may be so designed that a duplex operation or alternative operation in both directions of traffic is possible over the telegraph lines.

An embodiment of our invention employing the above described repeating equipment is illustrated in Fig. 2 of the drawings. This figure shows diagrammatically the connection of two subscribers TS and TS' which can be connected by one or a plurality of central offices or exchanges, for instance the two offices A and B. The connection may partly take place across toll lines, for instance L_1 and L_2 .

One central office A may simultaneously subdivide the toll line in a suitable manner. The connection, for instance, from the subscriber TS to the subscriber TS', takes place in well-known manner by operating selectors WS_1 , WS_2 , WS_3 in a plurality of selector steps. The selectors WS_1 and WS_2 , may, for instance, be accommodated in the central office A, further selectors WS_3 in the office B. In the central office A there is furthermore housed a correcting repeater EU which corrects the telegraph impulses, but in the position of rest or up to the complete through-connection is bridged over by a bypass Y or disconnected altogether. The starting of the repeater takes place only when the telegraph impulses are transmitted or when the through connection has been completed.

Figs. 3 to 6, which are partial views related to one another as indicated in Fig. 7, show a diagram of connections of the subscriber's apparatus and switching arrangements necessary for setting-up a connection, only the parts which facilitate the understanding of our invention being shown.

Fig. 3 shows on the left-hand side the essential current elements of a subscriber's station TS, which consist of a receiving relay E and a transmitting contact S. The supply of current takes place through a transmitting potential divider ST, which may, for instance, be fed from the alternating current supply through a rectifier.

The subscriber station is connected with the central office by four-wire lines, each of the two pairs of wires being provided for the traffic in one of the two directions. It will be understood, however, that it is also possible to employ other systems of transmission.

more particularly such for which only two-wire connecting lines are required.

At the central station the impulses dispatched by the subscriber TS are received by a receiving relay ER, while the dispatch of impulses to the subscriber takes place by a transmitting relay ES.

Every circuit to be set up passes within the central office first over a pre-selector VW which in a well-known manner selects a line leading to an idle group selector or final switch respectively. The busy test is made by means of a testing relay T which is connected to a pilot wire *c* combined with one of the two main traffic lines *a*, *b*. There is also apportioned to each subscriber an answering or back ring device AN which will be more fully discussed later on.

From the pre-selector VW the connecting lines lead to the final switch or connector LW, which together with the switching arrangements pertaining thereto is illustrated in Fig. 4. In front of the final switch there is, however, connected a repeating device serving for the correction of the signals, and which is shown in Fig. 5 of the drawings. This repeater device consists of two substantially similar correcting repeaters, which are provided for the two directions of traffic, each consisting of a receiving distributor, a transmitting distributor and a group of storing relays.

From the final switch LW shown in Fig. 4 the connecting lines are extended to the pre-selector connection VW' (see Fig. 6) of the called subscriber. The connection may be made through a sub-station ZA in which further selectors are located. This station may, however, be part of the central station. With the pre-selector VW is connected an automatic answering or back ring device AN' which when the through connection is completed transmits a signal from the called party, more particularly his name and, if desired, the address, as a check for the calling party that the correct connection has been completed. The diagram of connections of the called party TS' is shown on the right-hand side of Fig. 6. The diagram of connections according to Fig. 6 is otherwise identical with the diagram of connections illustrated in Fig. 3 for the calling party TS.

In describing the mode of operation of the system it is in the following assumed that the subscriber TS wishes to communicate with the subscriber TS'.

For the purpose of calling up the central office the transmitting contacts (Fig. 3) are first turned from the position of rest shown ("false position of rest") into the service position of rest, so that the direction of the current in the receiving relay ER of the central office is reversed. The switching on of the potential divider ST may have taken place previously by a special manipulation.

The reversal of the direction of the current in the relay ER of the central office causes the changing-over of the contact *er* whereby the following circuit for the relay X is completed: positive pole of the source of current, UA₁, SS₁, X, *er*, SS₂, UA₂, negative pole. UA₁ and UA₂ are overload circuit breakers which like the fuses SS₁ and SS₂ serve to protect the sources of current as well as the apparatus.

By the response of the relay X the pre-selector VW is marked and simultaneously engaged, an auxiliary relay R first being connected in circuit by the contact *x*₁, in the following circuit: positive pole, *x*₁, R, fuse SS₃, overload circuit breaker UA₃, negative pole. The contact *x*₂ prepares the connection through the ring wire. The relay R closes with its contact *r*₁ an exciter circuit for the rotary magnet DV of the pre-selector VW, so that it starts in the circuit: positive pole, wiper *vd* of the pre-selector, *t*₂, *r*₁, DV, SS₄, RU, UA₄, negative pole. By the interrupting contact RU, which may, for instance, be a relay interrupter, the selector is turned until the final switch *vc* of the pre-selector has found the negative pole of an idle final switch LW (Fig. 4) and the pilot relay T is made to respond thereby in the circuit: positive pole, testing relay T, *vc*, *c*-wire to the final switch (Fig. 4), C, *c*₂, *k*₁, UA₄, negative pole. The testing relay T (Fig. 3) now disconnects the high-ohmic winding (2), so that through the circuit *r*₁, *t*₁, *vd*, positive pole only the low-ohmic winding (1) is now traversed by current. In this way is prevented a further seizure of the respective final switch.

By the contacts *t*₂ and *t*₄ the tip wire and the ring wire are connected through to the final switch after the wipers *va* and *vb* of the pre-selector have been set on to the connecting lines leading to this final switch or connector. The closing of the contacts *r*₂ and *r*₃, which has already taken place when switching in the relay R, remains first inoperative with the assumed direction of traffic. They are provided for the opposite direction of traffic (to the subscriber TS) and then serve for connecting the automatic answering or back ring device shown in the upper part of Fig. 3.

During the testing of the pre-selector VW for the idle or disengaged final switch LW (Fig. 4) the relay C pertaining to it has responded.

By the contact *c*₂ of the relay C, the *c*-wire, which had previously been passed is switched through the mechanical contact *k*₁ of the final switch LW, directly over to the negative pole thereby enabling the subsequent resetting of the selector. By the contact *c*₁ a circuit is prepared for the testing relay having two coils or windings *p*₁, *p*₂ while the reversal

of the contact c_3 enables the subsequent response of the relay U.

On connecting through the two traffic wires by closing the contacts t_3 and t_4 (Fig. 3) a circuit was furthermore completed for the transmitting relay ES, viz: centre M of the source of current at the central office, relay ES, resistance W_1 , t_4 , x_2 , v_b , b-wire (Fig. 4), p_2 , w_1 , SS_5 , UA_5 , minus pole. The direction 10 of the current in this circuit is such that the armature es of the transmitting relay ES is reversed from the position of rest shown into the service position of rest and thus by the reversal of the direction of the current in the 15 receiving relay E a "free" signal is given to the subscriber TS. This free or disengaged signal may consist of an acoustic or optic signal or may be utilized for starting the apparatus, for instance for connecting the 20 driving motor to the supply.

The resistance W_1 connected in series with the transmitting relay ES may, like the resistance W_2 , be provided for the balancing of the lines.

25 After receipt of the "free" signal the subscriber operates the dial in the usual manner and thus controls the transmitting contact s or an equivalent impulse contact so that by stepwise reversal of the direction of the current in the receiving relay ER of the office its armature is by intermittent motion reversed into the (illustrated) working position. In the working position of er the relay X is short-circuited every time, but this relay is 30 fitted with time lag mechanism so that it remains permanently attracted in spite of the intermittent short-circuiting; on the other hand the impulse relay A at the final switch LW (Fig. 4) is intermittently energized 35 every time the armature is changed over into the working position, which relay in the position of rest of the armature er is at both sides connected to the negative pole of the source of current at the office and is thus not 40 energized: positive pole, UA_1 , SS_1 , er , t_3 , va , tip wire (Fig. 4), p_1 , A, SS_5 , UA_5 , negative pole.

45 By the first series of impulses the lifting magnet H of the final switch LW is controlled in known manner by means of the impulse contact a_1 of the impulse relay A so that the first switch is lifted into the desired decade: positive pole, a_1 , V, u_2 , w_2 , H, UA_4 , negative pole. During the first lifting step the 50 mechanical contact h_1 is opened and h_2 closed, but the response of the relay U is prevented for the time being, as simultaneously with the first switching on of the lifting magnet H the time lag relay V connected in series 55 with the magnet is excited and the contact v_1 opened.

In consequence of its time lag the relay V remains constantly energized during the first 60 series of impulses and drops off only after completion of the series of impulses, i. e. when

the final switch stands in the desired decade. By the then closing contact v_1 , the following circuit is completed for the relay U: positive pole, mechanical contact h_2 , v_1 , c_3 , U (2), w_2 , H, c-wire, UA_4 , negative pole. 70

The relay U serves for changing over from lifting to rotating. Owing to the provision of the reversed contact u_3 the following series of impulses will not be conducted to the lifting magnet H but to the rotary magnet D which brings the final switch within the 75 decade reached into the desired contact position.

Up to the arrival of the second series of impulses the reversing relay U remains energized in the following circuit: positive pole, h_2 , v_1 , c_3 , U (2), w_2 , c-wire, UA_4 , negative pole. As soon as then the impulses of the second series arrive, the rotary magnet is stepwise energized in the following circuit: positive pole, impulse contacts a_1 , V, u_2 , p_2 , D, UA_4 , negative pole. During the first impulse the relay V is also energized which in its turn holds its armature attracted during the entire series of impulses. The excitation of the relay U is then maintained through the winding 1 in the circuit: positive pole, v_2 , u_2 , U (1), c-wire, UA_4 , negative pole. After the completion of the second series of impulses the circuit for the winding 2 of the relay U is again completed and maintained up to the response of the testing relay P. 85

The contact u_1 thus remains permanently open during the second series of impulses (rotating), so that the closings of the contact d taking place when the rotary magnet D is attracted remain inoperative since on the other hand the contact v_1 is also open during the series of impulses. These contacts become operative only when on completion of the traffic the selector should automatically be turned back into the inoperative position. The shaft contact w_2 serves the same purpose, 90 said contact holding the lifting magnet H disconnected up to the final resetting of the selector; by the second shaft contact w_1 , on the other hand, a changing over of the ring wire is effected, which on making the connection becomes operative when the line selected is busy. After the dropping off of the relay U a busy potential (+) is connected over the circuit u_4 , w_1 , p_2 , to the ring wire for the calling party. 95

100 As soon as the second series of impulses is completed the relay V drops open with time lag and by means of its contact v_2 closes a circuit for the testing relay P which when the connecting line to be extended is idle or the subscriber's apparatus is connected to the final switch contact, responds along the circuit: c-wire, wiper lc , c_1 , u_5 , v_2 , P (2), P (1), c-wire, UA_4 , negative pole. 115

120 The testing relay P now responds and short circuits by means of its contact p_4 the high- 125

ohmic winding (2), whereby a further seizure is prevented in known manner. By the contacts p_1 and p_2 the tip wire and the ring wire coming from the pre-selector (Fig. 3), are connected through to the repeating device (Fig. 5), and simultaneously the impulse relay A is disconnected so that further current impulses can pass only to the repeater and the further selectors respectively.

- 10 By the contact w_2 the energizing circuit for the relay U (2) has furthermore been broken so that finally this relay drops open. By the closing of the contact u_1 a circuit for the resetting of the final switch is then prepared while the contact u_4 connects the c-wire to the positive pole and closes an additional circuit for the already excited testing relay P along the circuit: positive pole, UA_6 , SS_6 , u_4 , c_1 , p_4 , P (1), c-wire, UA_4 negative pole.

The subscriber is now able to continue the selection. The impulses pass in the manner described through the tip wire to the contact p_1 at the final switch LW (Fig. 4), but are not, as before, conducted to the impulse relay A, but to the receiving relay E_1 of the repeater (Fig. 5), the armature of which, on being connected through (by the contact p_1), is first turned into the service rest position: positive pole (Fig. 3), UA_1 , SS_1 , er , t_3 , va , c-wire (Fig. 4), p_1 , tip wire (Fig. 5) E_1 , M. By the contact e_1 the impulses are retransmitted to the transmitting relay S_2 of the repeater along the circuit: positive pole, e_1 , EK_1 , h_3 , SK_1 , S_2 , M. The contact s_2 , which had likewise been turned into the service rest position, in its turn passes the impulses across the wiper la of the final switch LW (Fig. 4) to the further selectors located in the substation ZA (Fig. 6) along the circuit: positive pole or negative pole, s_2 , tip wire (Fig. 4), la , tip wire (Fig. 6), ZA.

In the office ZA further selectors are operated by the impulses in usual manner and finally the pre-selector VW' of the desired subscriber TS' is engaged by the energization of the relays I' and T' . Both relays are connected to the c'-wire and are made to respond in the following circuit: ZA, c'-wire, I' , vc' , T' (1), T' (2), vd' , positive pole.

By the testing relay T' the contacts t_3' and t_4' are closed and thereby the two transmission wires are connected through to the desired subscriber TS' .

During the through connection the relay ES' is changed over in the ring wire, so that by reversing the armature es' the receiving relay E' of the subscriber TS' also passes into the service rest position in which is effected the connection of the subscriber's apparatus. The transmitting contact S' is then also reversed so that in the central office the relay ER' is reversed and the relay

X' energized. By the contact x_1' the auxiliary relay R' is connected in circuit.

In the same circuit with the testing relay T' the relay I' is also made to respond, which with its contact i_1' prepares the response of the answering device and at the same time prepares a resetting circuit for the said device by opening the contact i_2' . This device, which is shown at the upper part of Fig. 6, consists of a rotary magnet DN' , which switches the wipers d_1' and d_2' stepwise forward. The forward motion takes place at regular intervals by means of a contact z' , which may be connected to the transmitter AN' of the answering device. As such transmitters, we may employ apparatus of the type described and illustrated in the pending application of August Jipp and others filed in the United States Patent Office on January 4, 1930, Serial No. 418,460.

As the relay I' is attracted and the contact i_1' thus permanently turned into the working position the rotary magnet of the answering device DN' receives an impulse every time the contact z' is closed over the circuit: positive pole, z' , i_1' , wiper d_1 , DN' , negative pole.

The wipers d_1' , d_2' are thus moved forward stepwise at regular intervals, until the wiper d_1' runs on to the last contact, across which it first receives no further impulse, as the contact i_2' is open.

During the stepwise forward motion of the wipers a definite sequence of impulses corresponding with a signal, is in every position transmitted through the wiper d_2' into the ring wire. The impulse combinations are produced in the transmitting device AN' of the answering device, one signal being apportioned to each of the transmitting lines SL' of the said device, which signal together with the others forms a characteristic, for instance the name of the called subscriber. Of the transmitting lines SL' only five are represented in the example illustrated, but it will be understood that their number may be larger or smaller according to requirements.

The impulse series dispatched by the transmitting apparatus AN' across the wiper d_2' of the answering device corresponding with the characteristic of the called subscriber pass over the ring wire b' , the selectors of the substation ZA, the ring wire and the final switch LW (Fig. 4) to the receiving relay E_2 of the transmitting arrangement (Fig. 5). The following circuit is completed: AN' (Fig. 6), SL' , d_2' , ring wire b' , ZA, ring wire (Fig. 4), lb , ring wire (Fig. 5), E_2 , M.

The connection illustrated is, as already mentioned, based upon the assumption that impulse sequences correspond with the five-unit code employed in printing telegraphs operating on the start-stop principle.

These five-unit code signals are initiated by a start impulse effecting the release of the receiver shaft and, as a rule, finished by a stop impulse. The start impulses of the signal combination dispatched by the answering device are so directed that they reverse the connection of the armature e_2 of the receiving relay E_2 in the transmission apparatus from the positive to the negative pole. The release magnet EM_2 of the repeater for the direction from the called to the calling subscriber is then made to respond so that the receiver wiper EB_2 is released and carried along by the revolving shaft of the repeater for one revolution. The speed of rotation of the shaft is adapted to the speed of the telegraphing signals so that a correct storage of the individual impulses occurs.

For storing the individual impulses of the received five-unit code the polarized relays $R_{21}-R_{25}$ are provided, which are connected on the one hand to the centre M of the source of current at the exchange, on the other hand to the segments 1 to 5 of the receiving contact disk. If during the rotation of the contact arm the receiving wiper EB_2 connects successively the segments 1 to 5 with the contact disk EK_2 and thus also with the armature e_2 of the receiving relay, then every time one of the contact segments connected with the impulse storing relay is swept by the wiper, such relay is reversed towards the positive or the negative pole, according to whether the armature e_2 of the receiving relay E_2 is in one or the other position. The five-unit code dispatched by the answering device is thus first transmitted to the storing relays.

An adequate time after the starting of the receiving wiper EB_2 the cam N_2 connected with it closes the contact n_2 , whereby the release magnet SM_2 is excited and now the transmitting wiper SM_2 is also released for one revolution. Simultaneously with the release of the transmitting wiper SB_2 , there is energized the auxiliary relay SH_2 connected in series with the release magnet SM_2 , which may be a neutral relay, and by the temporary reversal of the contact sh_2 the start impulse is transmitted to the transmitting relay S_1 along the circuit: negative pole, sh_2 , SB_2 , SK_2 , S_1 , M .

During its further revolution the transmitting brush SB_2 connects the contact disk SK_2 successively with the segments 1 to 5, which in their turn are connected to the armatures of the storing relays R_{21} to R_{25} . In this way the impulses stored up by the storing relay are transmitted to the transmitting relay S in accurately correct length and time sequence, the relay turning its contact s_1 in correspondence with the impulses towards the positive or negative pole.

From here the corrected impulses pass over

the pre-selector VW and the transmitting relay ES (Fig. 3), to the calling subscriber TS along the circuit: positive or negative pole, s_1 (Fig. 5), ring wire, n_2 (Fig. 4), ring wire, vb (Fig. 3), ax_2, t_4, W_1, ES, M . The contact es of the transmitting relay ES passes the impulses, in the manner described, to the receiving relay E of the subscriber TS , so that this subscriber receives the impulse combinations corresponding with the characteristic of the called subscriber and thus receives confirmation that the correct connection has been made.

It has been assumed that the receiving motor of the subscriber is switched in as soon as the subscriber receives the free signal of the central office, by reversing the armature es into the service position of rest. It is, however, also possible to effect the connection only when the reception of the characteristic or identifying signal of the desired party dispatched by the answering or back signal device begins. The switching-in could then, for example, take place by the first impulse or by a special combination of impulses which precede the characteristic signal proper.

To enable the interchange of telegrams to be commenced, it is necessary to eliminate the by-pass of the correcting impulse repeater (Fig. 5) provided for the direction from the calling subscriber to the called subscriber. This is preferably effected by the repeater provided for the opposite direction of traffic on reception of the confirmation by the answering device, but it will be understood that another switching process occurring after the extension of the connection may, of course, also be utilized for eliminating the by-pass or for starting the repeater. If the characteristic dispatched by the answering device is employed for initiating the necessary switching process, a special combination of impulses may, for instance, be employed, which renders operative a receiving apparatus responding exclusively to this combination of impulses and thereby brings about the elimination of the by-pass. The impulse combination may during the recall be transmitted at any desired period for instance at the beginning or at the end of the return call.

In most cases it will, however, suffice if only some, for instance two, impulses of a combination signal comply with a certain condition. For the repeat arrangement illustrated in Fig. 5 it is, by way of example, assumed that the first and the last impulses of the five-unit code must have opposite directions of current. On receipt of such a signal the armatures of the storing relays R_{21} and R_{25} will have opposite positions, so that a circuit for the holding relay H (1) is completed. The holding relay disconnects itself automatically by its contact h_1 but simultaneously a circuit for the other winding (2) of the holding relay is completed

through the contact h_2 , viz: positive pole, contact c_4 (Fig. 5) of the relay C (Fig. 4), h_2, H (2), negative pole.

The holding relay H thus remains permanently energized until it is on breaking the connection made to drop off by opening the contact c_4 . The holding relay will drop off only when the armatures of the storing relays R_{21} and R_{25} are in the same position.

10 The last of the transmitted signals must thus have a certain property, but this condition can easily be fulfilled, as for the purposes of disconnection or clearing a special clearing signal is generally transmitted.

15 During the response of the holding relay H the contacts h_3 , h_4 and h_5 are also reversed whereby the correcting impulse repeater, provided for the direction from the calling to the called subscriber, is made ready for 20 service.

If telegraph signals are now dispatched from the calling subscriber, these pass first, in the manner described above, to the receiving relay E_1 of the repeater apparatus, but 25 they are not, as before, transmitted directly from the armature e of this relay to the transmitting relay S_2 , but pass, as h_3 is open and h_4 is closed, to the release magnet EM_1 of the receiving wiper EB_1 along the circuit: 30 negative pole, e_1 , EK_1 , EB_1 , h_4 , EM_1 , positive pole. It is to be noted that the service position of rest of the armature e_1 is not at once identical with the position of rest illustrated, and that, as described above, the armature e_1 is reversed into the service position of rest only during the making of the connection.

40 After the release of the receiving wiper EB_1 by the start impulse the individual impulses corresponding with the five-unit code are passed to the storing relays R_{11} to R_{15} , in the manner already described for the other repeater, by being connected in succession to the contact disk EK_1 through the contact segments 1 to 5.

45 The release of the transmitting wiper SB_1 takes place a short time after the start of the receiving brush EB_1 , as soon as the release magnet SM_1 is energized through the cam contact n_1 . Simultaneously the start impulse to the transmitting relay S_2 is transmitted by the auxiliary relay SH_1 through the closed contact h_5 of the holding relay H along the circuit: negative pole, sh_1 , h_5 , contact segment O, SB_1 , SK_1 , S_2 , M. The transmission of the remaining signal impulses takes place when the transmitting wiper SB_1 sweeps over the segments 1 to 5.

50 The corrected impulses pass from here over the tip wire and the final switch LW (Fig. 4) to the substation ZA (Fig. 6) and hence to the desired subscriber TS' . The circuit is as follows: positive or negative pole, s_2 (Fig. 5), tip wire, la (Fig. 4), tip wire, ZA (Fig. 6), tip wire a' , t_4 , W_1' , ES' , M.

The armature es' of the transmitting relay ES' then controls the receiving magnet E' at the subscriber's station ES' .

The impulses to be transmitted from the called subscriber TS' to the calling subscriber TS take the following path: The transmitting contact s' controls the receiving relay ER' at the office of the called subscriber TS' . The contact er transmits the impulses through the contact t_3' of the testing relay T' , the contact r_3' of the auxiliary relay R' , the wiper d_2' of the answering device and the ring wire b' to the substation ZA . After the completion of the answering signal, this connecting line is connected through by the wiper d_2' of the answering device as soon as the wiper has reached the last contact. In this position the exciter circuit for the rotary magnet DN' of the answering device is interrupted when the wiper d_1' runs on to the last contact as already described.

From the substation ZA the impulses pass through the ring wire to the wiper $1b$ of the final switch LW (Fig. 4) and from here over the tip wire to the receiving magnet E_2 of the repeating apparatus (Fig. 5). The further transmission of the telegraph signals occurs in exactly the same manner as described above for the transmission of the confirmation by the answering device.

The release of the connection can take place from either one or the other of the two subscribers. If, for instance, the calling subscriber TS turns the transmitting contact s from the service position of rest back into the position shown ("false position of rest"), the contact er of the receiving relay ER at the central office is likewise constantly turned back into the position of rest shown. The relay X is thus short circuited so that it releases with time lag and also causes the relay R to release by opening its contact x_1 . Before the slow release of the relay R takes place and its contact r_2 opens, a circuit for the transmitting relay ES is completed by the reclosing of the contact x_2 which moves the armature of this relay back into the position of rest shown, viz positive pole, UA_1 , SS_1 , resistance W_2 , r_2 , x_2 , t_4 , resistance W_1 , ES , M.

By reversing the contact es the direction of the current in the receiving magnet E of the subscriber TS is likewise reversed. This procedure may preferably be utilized for disconnecting the transmitting and receiving gear or the driving motor at the subscriber's station. The auxiliary circuit for the relay ES is interrupted as soon as the relay R has released and the contact r_2 is opened.

The contact r_4 interrupts the circuit for the winding (1) of the testing relay T so that the relay releases. The contact t_1 then closes the restoring circuit for the pre-selec-

- tor VW, which is thereby moved into the initial position: positive pole, vd continuous segment, t_1 , rotary magnet DV, SS₄, relay interrupter RU, UA₃, negative pole.
- 5 The pre-selector is arrested as soon as it has attained its original position in which the exciter circuit for the rotary magnet is interrupted. By the contacts t_3 and t_4 of the testing relay the through connection of the
- 10 two traffic wires had been eliminated, so that during the rotation of the pre-selector any breakdown of the switchgear connected with the pre-selector contacts is effectively avoided.
- 15 Simultaneously with the testing relay T of the pre-selector VW (Fig. 3) the relay C at the final switch LW (Fig. 4) has released. By the contact c_3 the restoring of the final switch is then prepared while the contact c_1 releases testing relay P of the final switch. The contacts p_1 and p_2 disconnect the traffic wires a and b leading to the repeater device, while simultaneously the new connection is prepared by switching on the impulse relay A.

The contact p_3 of the testing relay P closes an exciter circuit for the rotary magnet D of the final switch, the wipers being thereby rendered operative: negative pole, UA₄, D, p_3 , u_1 , c_3 , v_1 , k_2 , positive pole. When the rotary magnet attracts, it closes its contact d , which causes the relay U to respond in the circuit: positive pole, k_2 , v_1 , d , U (1), c-wire, UA₄, negative pole. The relay U pulls up and opens the contact u_1 whereby the exciter circuit of the rotary magnet D is interrupted and its armature drops off again. This breaks the contact d so that the relay U releases again. By closing the contact u_1 the rotary magnet D is switched in again and the relay U is energized again.

This alternate switching on and off in the manner of relay interrupter continues until the final switch has in the course of its rotary motion attained the last position in which it automatically drops back into the initial position. During this dropping back the mechanical contacts k_1 and k_2 are reversed, a fresh exciter circuit for the relay C being prepared by k_1 and the automatic interrupter circuit of the rotary magnet being interrupted by k_2 .

During the resetting of the final switch the shaft contact w_1 is also reversed in the end position, and connects the ring wire b' again to the negative pole and thus eliminates the seizure of the final switch. The contact w_2 prepares the circuit for the lifting magnet H which should become operative when the next connection is made. By disconnecting the c-wire, resetting of the engaged selectors in the substation ZA (Fig. 6) is caused.

By the release of the relay C at the final switch LW (Fig. 4) the contact c_4 which

forms part of the repeating apparatus (Fig. 5) is broken again so that the holding relay H releases and by the resetting of the contacts h_3 , h_4 and h_5 into the position shown causes the by-passing for one of the two repeaters.

After the resetting of the selectors in the substation ZA (Fig. 6), the c-wire leading to the pre-selector VW' of the called subscriber is interrupted so that the relays I' and T' release. The contact i_2' then connects up for the answering device, which is in the last position a relay interrupter UN' which moves the wipers of said device into the initial position, in the circuit: negative pole, DN', d_1' , i_2' , UN', positive pole. The rest contact i_1' is provided only for the case that the subscriber should bring about the release of the selectors already during the giving of the answering signal. The forward motion of the answering device into the position of rest is then effected through the wiper d_1' and the continuous segment, in the circuit: negative pole, DN', d_1' , u_1' , UN', positive pole.

During the release of the testing relay T' the contacts t_3' and t_4' were broken and thereby the traffic wires a' and b' interrupted. Prior to this the direction of the current in the transmitting relay ES' was already reversed during the changing-over of the transmitting contact s at the calling subscriber TS to the normal path used for transmitting the telegraph signals, and thus the armature es' of this relay was permanently turned back into the position of rest shown. In this way the receiving relay E' at the subscriber's station TS is reversed whereby the subscriber's apparatus is switched off and the transmitting contact s' is positively moved from the service position of rest into the position of rest shown. This reversing of the relay ER' at the central office then causes the resetting of the contact er' and the release of the relay X' in the manner described above. The relay X' disconnects in its turn with its contact w_1' the auxiliary relay R' which opens with a slow action.

The whole plant is now again in the inoperative state.

We claim as our invention:

1. In a telegraph system comprising a plurality of line sections and regenerative telegraph repeaters interposed between contiguous line sections for transmitting telegraphic signal currents, electrically controlled means for disconnecting and by-passing said telegraph repeaters.

2. In a telegraph system comprising a plurality of line sections and regenerative telegraph repeaters interposed between contiguous line sections for transmitting telegraphic signal currents, electrically controlled means for disconnecting and by-passing said telegraph repeaters, the control of said means being effected by the initiation and the termination of the telegraphic communication.

3. In a telegraph exchange system comprising a plurality of subscribers' stations, one or more central stations, switch means at said central station or stations for establishing connections between said subscribers' stations, and regenerative telegraph repeaters for the transmission of telegraphic signal currents; means for switching said repeaters into connections established between said subscribers' stations, relays controlling the last-mentioned means, and means for actuating said relays by the establishing of said connections.

4. In a telegraph exchange system comprising a plurality of subscribers' stations, one or more central offices, switch means at said central office or offices for establishing connections between said subscribers' stations, and regenerative telegraph repeaters for the transmission of telegraphic signal currents; means by which a special impulse combination is sent back on extending the connection to the called subscriber's station, and means for switching said telegraph repeaters into connections established between said subscribers' stations, said last-mentioned switching means being controlled by said special impulse combination.

5. In a telegraph exchange system comprising a plurality of subscribers' stations, one or more central offices, switch means at said central office or offices for establishing connections between said subscribers' stations, and regenerative telegraph repeaters for the transmission of telegraphic signal currents; means for producing predetermined impulse combinations, and means for switching said telegraph repeaters into connections established between said subscribers' stations, said last-mentioned switching means being controlled by only a portion of the individual impulses constituting an impulse combination.

6. In a telegraph exchange system comprising a plurality of subscribers' stations, one or more central offices, switch means at said

central office or offices for establishing connections between said subscribers' stations, and regenerative telegraph repeaters for the transmission of telegraphic signal currents; means for switching said telegraph repeaters into connections established between said subscribers' stations, and an answering or back signal device controlling the last-mentioned switching means, said device being arranged to send to the calling subscriber's station, if the called subscriber's station is disengaged, a characteristic identifying the latter station.

7. In a telegraph exchange system comprising a plurality of subscribers' stations, one or more central offices, switch means at said central office or offices for establishing connections between said subscribers' stations, and regenerative telegraph repeaters for the transmission of telegraphic signal currents; means for switching said telegraph repeaters into connections established between said subscribers' stations, an answering or back signal device controlling the last-mentioned switching means, a relay for actuating said device, and means for causing said relay to respond when the desired connection has been established.

8. In an automatic telegraph exchange system comprising a plurality of subscribers' stations, one or more central offices, automatic switch means at said central office or offices controlled by dialling impulses from said subscribers' stations for establishing connections between said subscribers' stations, and regenerative telegraph repeaters for the transmission of telegraphic signal currents; means for transmitting said dialling impulses under simultaneous by-passing of said telegraph repeaters.

In testimony whereof we affix our signatures.

ERICH KRUHME,
AUGUST JIPP,
EHRHARD ROSSBERG.
